UNITED STATES PATENT OFFICE.

AARON CARVER, OF LITTLE FALLS, NEW YORK.

IMPROVEMENT IN PUMPS FOR DEEP WELLS.

Specification forming part of Letters Patent No. 57,086, dated August 14, 1866.

To all whom it may concern:

Be it known that I, AARON CARVER, of Little Falls, in the county of Herkimer and State of New York, have invented a new and useful Improvement in Pumps for Oil and other Deep Wells; and I do hereby declare that the following is a full, clear, and exact description thereof, which will enable those skilled in the art to make and use the same, reference being had to the accompanying drawings, forming part of this specification, in which—

Figure 1 is an axial section of a pump made according to my invention. Fig. 2 is a peripherical view of the detachable box that contains the lower valve of the pump; Fig. 3, an inverted view of the bottom of the pump-cylinder.

Similar letters of reference indicate corresponding parts.

The object of this invention is to produce a single-acting pump for use in oil and other deep wells, and which is especially adapted for wells that discharge gas along with liquids.

The invention consists in several novel features, one of which is the manner of locking the box of the lower valve in the pump, so that it cannot be driven upward out of its place by the pressure of gas from below. Another is the manner of unlocking the valve-box so that it may be drawn up out of the pump-tube by the piston-rod. Another is carrying off any gas which may be in the well through a gas-chamber that is independent of the pump-cylinder and that communicates with the pump-tube above the piston. Another is the manner of arranging and securing the pump-cylinder within an outer cylinder which contains the gas-chamber.

A designates the piston of the pump. The piston is hollow, having inlet-openings through its sides near its end, which openings are closed by a tubular valve which contains the packing of the piston, and which has enough motion over the piston lengthwise to open and close the inlet-openings as the pump is worked. The discharge-openings of the piston are on its upper end, where it is connected to the piston-rod, around which the oil or other liquid is discharged into the pump-cylinder. The lower end of the piston has a left-hand screw-thread formed on it, by which the valve-box of the pump can be engaged, as hereinafter

described. The piston works in a cylinder B, which is connected above to a pump-tube that is carried to the top of the well.

The bottom of the cylinder terminates in a disk, C, which is set eccentrically thereon, as shown in Fig. 3. The inlet D to the lower valve of the pump is made through the disk, and thence up through the lower end of the cylinder. Through that part of the disk which extends beyond the circumference of the cylinder is a passage, E, for the admission of gas from the well into a chamber, L, herein-after described. The valve-box F, which contains the induction-valve of the pump, is seen in Fig. 2. In its neck is formed an internal screw-thread, made so as to receive the left-hand screw-thread on the end of the piston, and openings U are made through its sides, just below the line of the internal screw-thread and above the cage which limits the ascent of the valve, to allow the displacement of oil or other liquid when the end of the piston is screwed down, the diameter of its neck being reduced so as to form an annular space between it and the sides of the pump-cylinder, into which space the displaced oil or other liquid may flow from the neck and top of the valve-box. The body of the box is extended below the line of its valve-seat, and upon the extension, at opposite sides, are formed hooks made so as to become engaged with certain pins H H within the cylinder only when they are moved toward the left, which hooks interlock with said pins H, that project inward from the opposite sides of the pump-cylinder near its lower end. When the valve-box is to be placed in position for working the piston is screwed into its neck and the box is inserted into the pump. When it has reached the bottom of the cylinder the piston-rod is rotated toward the left, when the hooks G will become interlocked with the pins H, only one of which is shown in the drawings. The piston is unscrewed and disengaged by turning the piston-rod in the opposite direction, and is then ready to be operated. By locking the valve-box in the cylinder I prevent it from being driven upward out of its place by pressure of gas from below, thereby preserving the valve and the piston from injury from this cause and keeping the lower valve always in proper position for being operated.

It will be observed that by making the

screw-thread on the end of the piston left-handed the joints of the piston-rod will be tightened when the rod is turned to the left to engage the valve-box, its joints being made with right-hand screw-threads.

Any other suitable locking device may be employed to secure the valve-box in place which can be disengaged by means of the piston.

Around the pump-cylinder, near its upper end, I form an eccentric ring, I, whose eccentricity is on the same side of the cylinder with that of the disk C below. The diameter of the cylinder through this ring is equal to that of an outer cylinder, J, which incloses the pump-cylinder, as shown in the view given in Fig. 1.

The pump-cylinder is set eccentrically within the outer cylinder, thereby leaving a crescent-shaped chamber, K, between them at one side, which chamber is closed at top by the eccentric ring, which serves as a cap therefore, and at bottom by the disk C, which, however, is received within the cylinder J. The cylinder J extends a little way below the bottom of the pump-cylinder, and the latter is secured in place therein by means of a ring, L, which screws up within cylinder J. This ring has projections on its lower end, which come below said cylinder and serve as legs to the pump to keep it above the bottom of the well.

The upper part of the pump-cylinder has an opening, M, a little below the eccentric ring or cap I, which makes a communication between the chamber K and the pump-cylinder. This opening M occurs at such a height as to be above the point reached by the piston in its upward stroke, and therefore it establishes constant communication between the chamber K and the pump tube.

The chamber K is provided for the purpose of receiving and conducting away any gas that may be present in the well. It is found very difficult to operate wells in which much gas is present, and sometimes the pressure therefrom is so great as to drive up the piston and piston-rod and stop the engine, sometimes also breaking the connecting-rod and walking-beam and other parts of the machinery. This is especially true in the case of single-acting pumps. My invention removes this difficulty by means of the gas-chamber K, which I form alongside of the pump. This chamber has a valve, N, fitting to a seat over the inlet E, the valve being placed within a cage, so that it will always be guided back upon its seat after being raised. The course

of the gas is through the valve-opening E, up through the gas-chamber L, through the opening M, into the upper part of the pump above the piston, and thence into the pump-tube, through which it escapes into the air without injuring the pump or hindering the working thereof.

I have here shown the gas-chamber formed on the outside of the pump by means of an inclosing-cylinder; but it may be formed by means of a pipe soldered or otherwise connected to the pump, and extending from the opening M down to the place of the opening E. It may also be formed by making a double wall around the whole or a part of the pump.

By means of this part of my invention I enable one to use a single-acting pump in an oil or other well without injury or hinderance from gas.

The valve N will, in the operation of the pump, be independent of the action of the piston, since the chamber K will be filled with oil or other liquid from the pump-tube or from that part of the cylinder above the piston. The column of oil or other liquid will keep the valve closed until such time when the pressure of gas is sufficient to overcome the weight of the column that fills the chamber K and the pump-tube, when the valve will be raised, and the gas will be conducted harmlessly away without affecting the operations of the pump.

I claim as new and desire to secure by Letters Patent—

1. The pump-cylinder, in combination with an outer cylinder, J, within which it is eccentrically placed, so as to form a chamber, L, between them, substantially as described.

2. Locking the valve-box of a pump within the cylinder so that it cannot be displaced by pressure from below, substantially as described.

3. Making the diameter of the neck of the valve-box less than that of its body, and perforating it, as described, to allow any liquid in the valve-box to escape and make way for the end of the piston when the latter is screwed into the neck of the valve-box, substantially as above set forth.

The above specification of my invention signed by me this 13th day of December, 1865.

A. CARVER.
